ELECTRICAL TERMINAL

David E. Welsh, Arcadia, Calif., assignor to Scanbe Manufacturing Corporation, El Monte, Calif.

Filed Mar. 9, 1972, Ser. No. 233,393

Term of patent 14 years

Int. Cl. D13—03

U.S. Cl. D26—1 E

FIG. 1 is a front view of an electrical terminal showing my new design;

FIG. 2 is a side elevational view thereof;

FIG. 3 is a top plan view thereof; and

FIG. 4 is a bottom plan view thereof.

I claim:

The ornamental design for an electrical terminal, as shown.
